UNITED STATES PATENT OFFICE.

FRANKLIN A. STEARN, OF PATERSON, NEW JERSEY, ASSIGNOR TO WESTERN ELECTRIC COMPANY, INCORPORATED, OF NEW YORK, N. Y., A CORPORATION OF NEW YORK.

MACHINE-SWITCHING SELECTOR-SWITCH CIRCUIT.

Application filed July 1, 1924. Serial No. 723,473.

This invention relates to a telephone exchange system, and more particularly to the control and operation of selector switches in a machine switching system.

5 It is an object of this invention to provide an improved method of operating selector switches.

In machine switching offices, common senders are provided having registers which are 10 positioned by dial interruptions transmitted thereto from subscribers' stations to register the designations of wanted lines. These senders are used to control the movement of selector switches to establish talking connections between subscribers' lines. A majority 15 of the selector switches in a machine switching office employing power driven switches are directed by the sender for brush selection and group selection, and after group selection are further controlled in a trunk 20 hunting movement. In order that the different selective operations of a selector switch may be successively performed in the proper sequence, a so-called sequence switch is 25 associated with each selector. The sequence switch is provided with a number of contact closing cams, and during the operation of a selector switch moves through a plurality of positions to variously close its cam 30 contacts. Its movement and the operation of apparatus for its control occupies an appreciable amount of time for each selector switch associated in sequence to complete a call from one subscriber to another. For 35 this reason it is desirable to combine operating functions to limit the apparatus of a selector switch and the number of cam contacts on its associated sequence switch and the amount of time required in selecting the 40 talking conductors.

A feature of this invention is in the provision of means in a sender and selector switch whereby group selection and trunk hunting may be made by a combined single 45 function of the selector switch.

A further feature of this invention is in the provision of means whereby banks of terminals associated with selector switches may be subdivided into groups to include 50 any number of terminals within the limits of each bank.

This and other features of the invention

will be apparent from the following description taken in connection with the accompanying drawings.

55

While the invention has been disclosed as particularly adapted for use with selector switches in panel type machine switching offices, it is apparent from the following description that the invention has a wider utility and that by slight modification it could be adapted for other types of switches.

60

Referring to the drawings, Figs. 1 to 3 and Fig. 1^A, inclusive, when arranged in the order illustrated by the diagram in Fig. 4, 65 disclose in detail the circuits and apparatus of a panel type machine switching system embodying the principles of the present invention for combining the group selection and trunk hunting into one function in the 70 operation of a selector switch.

65

Fig. 1 illustrates a subscriber's station K, a line circuit and a line switch. The line switch is of the type well-known in the art 75 for selecting an idle district selector switch.

75

Fig. 1^A illustrates the sender in diagrammatic form, embodying the principles of the present invention arranged to control a selector switch in such manner that the group selection and trunk hunting is made in a 80 single upward movement of the selector switch brushes.

80

Fig. 2 illustrates a district selector switch for selecting an idle sender and for selecting an idle office selector switch, as directed by 85 the sender.

85

Fig. 3 illustrates an office selector switch embodying the principle of the invention to combine the group selection and trunk hunting into a single operating function.

90

The subscriber's station, line switch and district selector switch are the same as described in detail in Patent No. 1,505,171, issued to the applicant August 19, 1924. The sender used to control the selector switch is 95 the same as described in detail in my above-mentioned patent with the modification shown in Fig. 1^A for controlling the office selector switch (Fig. 3).

95

General description.

100

A subscriber initiates a call by the removal of the receiver from the switchhook. This operation causes the line relay

to operate and line switch 100 to rotate for the selection of an idle district selector switch, as illustrated in Fig. 2. Upon the selection of the idle district selector the line switch is arrested in its forward movement and the apparatus of the district selector is operated to select an idle sender. The apparatus of the sender is then positioned by the operation of the dial in accordance with the office code and number of the wanted subscriber's line. The interruptions from the dial position the registers (not shown) in the sender to control selector switches. Each selector switch is directed by the sender for brush and group selection, and each switch in the train except the last then hunts for an idle trunk or line associated with the next selector switch to be used in the train of switches for the association of the calling subscriber with a particular office and with a particular line in said particular office. The last selector switch in this train of switches is directed by the sender to a particular line. This switch is not pertinent to the invention and is not shown. The district selector switch shown in Fig. 2 is operated in the manner described in Patent No. 1,505,171, issued to the applicant August 19, 1924, and does not incorporate the combined group selection and trunk hunting feature of this invention. This feature, however, may be applied to this type of selector switch as well as the selector switch shown in Fig. 3.

Assuming that the district selector switch (Fig. 2) has selected an idle sender and has been directed by said sender to associate a set of its brushes with conductors 313, 314 and 353 of the office selector switch (Fig. 3), the apparatus of the sender is operated to direct the selector switch (Fig. 3) for brush selection which positions the brush set 330 upon the first set of terminals of its associated bank 340. Upon the completion of brush selection, the brushes 331, 332 and 333 are brought into engagement with the first terminals of bank 340 and a circuit is completed from the grounded battery associated with said first set of terminals to the stepping relay of the sender. Let it be assumed that the sender is positioned for office group selection and that brush set 330 of the office selector is then driven in an upward movement. Each association of the sleeve brush with the first terminal in a group of bank 340 operates the stepping relay 152 in the sender. The operation and release of the stepping relay establishes circuits to operate the counting relays of the sender. When a number of counting relays have been operated in accordance with the position of a particular sender register, the 0 and 0' counting relays and relay 151 are operated. The operation of the sender maintains the energization of the up-drive

magnet in the office selector switch (Fig. 3) to continue the upward movement of brush member 330 until idle terminals to a succeeding selector switch have been selected.

It is apparent from the above description that no separate operating function is necessary in the office selector switch (Fig. 3) to initiate and control the trunk hunting function of said selector switch. It will be further noted that no commutator is used during group selection and trunk hunting with the exception of a centering commutator 342 which has a segment for each terminal. When a commutator, common to a plurality of banks is used for group selection, it is usually necessary to sub-divide all banks uniformly into groups. With the arrangement shown in Fig. 3, the banks may be subdivided into groups, each group to include any number of terminals within the limits of the bank and the grouping in each of a plurality of banks in a frame may be different. The advantage in the use of this arrangement is that any number of trunks within the limits of a bank, extending to a particular office may be connected to terminals of the bank to form one of the groups in the bank.

Detailed description.

Let it be assumed that the calling subscriber K desires to establish a connection with a subscriber's line. The calling subscriber upon initiating a call removes the receiver from the switchhook. This operation establishes a circuit to operate line relay 101 from grounded battery through the right winding of relay 101, the innermost lower contact of cutoff relay 102, line conductor 103 through the sub-station apparatus of line K and thence over line conductor 104 to ground at the upper contact of relay 102. The energization of the line relay establishes a circuit to energize stepping magnet 105 from grounded battery through the winding and contact of magnet 105, conductor 106, the lowermost contact of relay 102, right contact of relay 101, conductor 107 and thence to ground through the brush 108 and its associated contact. Magnet 105 operates opening its contact and releases to advance the brushes of the switch to the second terminals of the respective banks with which they are associated. The second terminal associated with brush 108 is connected to ground and magnet 105 again operates to advance the brushes to a third set of terminals leading to the first of the group of trunks connected to district selector switches such as shown in Fig. 2.

If the first trunk of the group is busy, ground potential is associated with the brush 108 and its associated contact and the switch continues to step until an idle trunk is found. An idle trunk is characterized by

battery potential from the district selector switch. When this battery potential is encountered, a circuit is established from grounded battery through the contacts of cam 202 of the district selector to which the first idle trunk extends, through the left inner contacts of relay 226, test conductor 114, brush 108 and its associated contact, conductor 107, the left contact and left winding 10 of relay 101, conductor 115 to ground through both windings of relay 102. Relay 102 is operated in the circuit traced to open the energizing circuit for magnet 105 and to extend the line conductors to the district selector switch, Fig. 2. The operation of relay 102 further establishes a circuit through its intermediate contact to energize sleeve relay 226. This circuit may be traced from grounded battery through the left winding 20 of relay 226, left normal contact of relay 227, right lower contact of cam 203, sleeve conductor 118, brush 109 and its associated contact, winding of message register 119, conductor 120, the intermediate contact of relay 102 to ground through the upper winding of relay 102.

Upon the energization of sleeve relay 226, a circuit is established to operate relay 228, which circuit extends from grounded battery through the right winding of this relay, upper contacts of cam 204, right contact of relay 226, and thence to ground through the right upper contact of cam 205. At its left inner contact, relay 226 connects ground potential to the test conductor 114 of the selected trunk to mark the trunk busy to other line switches. The locking circuit for line relay 101 is opened at the left inner contact of relay 226 to cause its release. The energization of relay 228 establishes a circuit to rotate sequence switch 200 out of position 1. This circuit extends from grounded battery through the magnet winding, lower right hand contact of cam 206, right inner contact 40 of relay 228 to ground at the right upper contact of cam 207. The sequence switch is thus rotated from position 1 to position 2 in which position, an operating circuit is established for relay 227 from grounded battery 45 through its left winding to ground through the left upper contact of cam 205. The operation of relay 227 closes a locking circuit for relay 228, extending through the left hand winding of relay 226, the left contact 50 of relay 227, thence to the sleeve conductor 118 over the right upper contact of cam 203. Upon reaching position 2, the sequence switch connects a new holding ground to the test conductor 114 at the left lower contact of cam 205. This holding circuit is 55 maintained until the district sequence switch is restored to normal.

When the district sequence switch reaches position 1 1/4, a circuit is established to operate stepping magnet 229 of the sender 60

finder switch. This circuit may be traced from grounded battery through the contact and winding of magnet 229, left lower contact of cam 208, right inner contact of relay 228 to ground through the right contact of 70 cam 207. A circuit is further established at this time through the winding of magnet 229, windings of relay 230 and 244 in parallel and thence to ground at the left upper contact of cam 209. Relays 230 and 244 do 75 not energize since their windings are shunted by the ground connected through the armature of relay 228.

When the sequence switch 200 rotates out of position 1, the initial energizing circuit 80 for relay 228 is opened at the upper contacts of cam 204, but this relay remains locked over a circuit extending from grounded battery through its left winding, its left contact, the lower right contact of cam 210, 85 lower left contact of cam 211, left outer contact of relay 226, brush 231 and its associated contact to ground on terminals associated with the brush extending to busy senders. Magnet 229 is energized under the 90 control of its self-interrupting contact to rotate the brush assembly until an idle sender is found. An idle sender is characterized by the absence of ground on the terminal associated with brush 231. When a terminal of 95 this character is encountered, the holding circuit for relay 228 is opened and it thereupon deenergizes. The release of relay 228 opens at its right inner contact, the energizing circuit for stepping magnet 229 to arrest 100 the rotary movement of the brush assembly. The release of relay 228 further establishes a circuit to energize sequence switch magnet 200, to rotate the sequence switch from position 2 to position 3. This circuit may be 105 traced from grounded battery through the magnet winding, left upper contact of cam 206, right inner contact of relay 228, to ground through the right contact of cam 207.

The release of relay 228 removes the shunt 110 from around the windings of relays 230 and 244 and the energizing circuit previously traced through their windings is now effective. The current through the winding of magnet 229 in this circuit is not of sufficient strength to cause its operation. The operation of relay 230 prepares circuit paths between the district selector switch and the selected idle sender and associates a ground with brush 231 to operate apparatus of the 115 sender to prepare it to receive dial interruptions from the subscriber's station. The operation of relay 244 also prepares circuit paths extending between the district selector switch and the sender.

When the sender is properly positioned, a dial tone is associated with the subscriber's 120 line and transmitted audibly to the subscriber through his receiver in the well known manner. The subscriber now oper- 125

ates the dial to produce circuit interruptions in accordance with the office code and number of the wanted subscriber's line designation. The interruptions from the dial open 5 the circuit extending to the sender over conductors 233 and 235, left contacts of relay 230, brushes 236 and 245 and their associated contacts over which the registers of the sender are set to record the digits of the 10 wanted line designation.

When the registers of the sender have been set, the district selector switch Fig. 2 is controlled by the sender code registers in such manner that one of its movable brush sets is 15 directed to an idle trunk associated with an office selector switch such as shown in Fig. 3. In this description, the district selector switch is directed by the sender for brush and group selection and trunk hunting in 20 the manner described in the aforementioned Patent No. 1,505,171. It may therefore be assumed that following the setting of the district selector switch the sequence switch Fig. 2 is rotated to position 10, and will re- 25 main in this position during the time the sender controls the succeeding switches of the train. Upon the association of the district selector switch with conductors 313, 314 and 353, a circuit is established to operate 30 relay 315, from grounded battery through its right winding, lower contacts of cam 304, conductor 313, terminal 257, brush 259, left upper and right lower contacts of cam 220, right outer contact of relay 230, brush 237 35 and its associated contact, lower contact of cam 155, right normal contact of relay 151, winding of stepping relay 804, conductor 157, and thence over the fundamental as shown in my aforementioned patent, return- 40 ing over conductor 156, lower contact of cam 154, brush 263 and its associated contact, left contact of relay 244, right lower and left upper contacts of cam 219, brush 258, terminal 256, conductor 314 to ground through the 45 left upper and lower contacts of cam 302. The operation of relay 315 establishes a circuit to energize sequence switch magnet 300 from grounded battery through its winding, left contact of cam 311 to ground through 50 the left contact of relay 315. The sequence switch is thus rotated from position 1 to position 2. During the rotation of the sequence switch, the energizing path for relay 315 is opened but a locking circuit is established 55 from grounded battery through its right winding, contacts of cam 303, right inner contact of relay 315, left upper contact of cam 308, thence over the fundamental to ground through the left contacts of cam 302. With 60 the sequence switch 300 in position 2, a circuit is established to energize up-drive magnet 321 from grounded battery through its winding, right upper contact of cam 311 to ground through the left contact of relay 315. 65 The movable brush shaft is driven upward

for office brush selection and the brush 345 is brought into engagement with commutator 341. During brush selection, the brush 345 intermittently establishes a shunt to operate and release the regular stepping relay 804 of 70 the sender for the operation of the correct number of counting relays in accordance with the positions into which the office code registers have been set. This shunt circuit may be traced from ground through the left lower contact of cam 312, brush 345 and connector 341, right contacts of cam 304 to a junction point in the fundamental circuit to cause the release of the sender stepping relay and the holding of the relay 315 in a 75 well known manner. Upon the completion of brush selection, the fundamental circuit is opened in the sender by the operation of the counting relays and relay 315 in the office selector switch is released. The release of 80 relay 315 arrests the upward movement of the brush shaft and brush 345, since the energizing circuit for updrive magnet 321 is opened at its left contact. The release of relay 315 further establishes a circuit to energize magnet 300 from grounded battery through its winding, left contact of cam 310 to ground through the left back contact of 85 relay 315. The energization of magnet 300 rotates the sequence switch from position 2 90 to position 3.

When office brush selection is completed, the sender rotates its sequence switch into position 10 in which position office group selection and trunk hunting take place. The fundamental circuit is now established in a different manner than the fundamental described for district brush and group selection and office brush selection. Upon the rotation of the sender sequence switch into position 10, a circuit is established to operate relay 150 from grounded battery through its winding, left normal contact of relay 151, to ground through the lower contact of cam 152. One leg of the fundamental circuit extends from grounded battery through the right winding of relay 315, left contacts of cam 304, conductor 314, terminal 256, brush 258, left upper and right lower contacts of cam 219, left contact of relay 244, brush 263 110 and its associated contact, lower contact of cam 154 to ground through the contact of relay 150. A second leg is established as a part of the fundamental circuit from ground through the winding of the sender stepping relay 152, right normal contact of relay 151, lower contact of cam 155, brush 237 and its associated contact, right outer contact of relay 230, right lower and left upper contacts of cam 220, brush 259, terminal 257, conductor 313, upper contacts of cam 308, brush 331, terminal 334, resistance 350 to grounded battery. This latter circuit is established as soon as brushes 331, 332 and 333 have been 115 associated with the first set of terminals of 120

the bank which takes place upon a subsequent upward movement of the brushes after the completion of brush selection and the energization of trip magnet 322. The circuit 5 to energize the trip magnet may be traced from grounded battery through the winding of this magnet to ground through the right lower contact of cam 309. The stepping relay 152 and the office circuit relay 315 are operated when each of the parallel paths of the fundamental circuits are established in positions 3 and 4 respectively of sequence switch 300.

The operation of relay 315 establishes a 15 circuit to rotate the sequence switch 300 from position 3 to position 4. The circuit for energizing the sequence switch magnet may be traced from grounded battery through its winding, left upper contact of cam 311, to ground through left contact of relay 315. Relay 315 is maintained operated in this 20 position of the sequence switch over the fundamental circuit previously traced.

Bank 340 is shown divided into groups 25 of equal numbers of terminals. The bank may, however, be subdivided into groups to include any number of terminals within the limits of the bank. A plurality of such banks are ordinarily associated with each selector 30 switch and each bank may be subdivided into groups with different numbers of terminals in the groups of each bank. Grounded battery through resistance 350 is connected to the first test terminal of each group or a terminal separating groups. Each time that 35 brush 331 is engaged with a terminal connected to resistance 350 and battery potential, a circuit is established to operate the stepping relay 152 in the sender. When brush 331 disengages a terminal connected to resistance 350, the stepping relay 152 releases. The operation and release of relay 40 152 operates counting relays in the sender to count the number of groups over which brush set 330 progresses. It will be noted that conductors 360, 361 and 362 are connected to terminals in the third group.

In sequence switch position 4, a circuit is established to energize the up-drive magnet 321 from grounded battery through the winding of this magnet, right upper contact of cam 311, to ground through the left contact of relay 315. Upon the energization of magnet 321, the brush set 330 is moved upward and the brushes 331, 332 and 333 brought into engagement with the bank terminals. It being assumed that a trunk terminating in the third group of bank 340 is to be selected the code registers of the sender will have been set to associate the #2 counting relay 158 with the contact of relay 152. The initial operation of the stepping relay 152 operates counting relay 158. The operation of counting relay 158 establishes a locking circuit for itself and an operating

circuit for counting the No. 2' counting relay, which is effective upon the release of stepping relay 152. On further upward movement of brush set 330, brush 331 is disengaged from terminal 334 to cause the release of relay 152 and upon the continued upward movement of brush set 330, brush 331 is engaged and disengaged with terminals 335 and 336, to cause the operation of counting relays No. 1, No. 1', No. 0, No. 0', 70 and relay 151 in a manner described for the operation for counting relays No. 2 and No. 2'. Relay 151 in attracting its right armature opens the fundamental circuit extending through the winding of stepping relay 80 152 and in attracting its left armature opens the energizing circuit for relay 150 and establishes a holding circuit for relay 150 over the fundamental circuit. This holding circuit may be traced from grounded battery 85 through the winding of relay 150, left alternate contact of relay 151, upper contact of cam 155, brush 237 and its associated contact, right outer contact of relay 230, right lower and left upper contacts of cam 220, brush 90 259, terminal 257, conductor 313, upper contacts of cam 308, brush 331, to the test terminals of the third group of bank 340. A busy trunk to a succeeding selector switch is characterized by ground associated with the 95 sleeve conductor. Assuming that the first and second trunks of the group are busy, relay 150 is maintained in an operated position during the upward movement of the brush set 330 over these terminals. The continued energization of relay 150 maintains a circuit through its contact for holding relay 315 operated and the continued energization of relay 315 maintains the energizing path for the up-drive magnet 321. Assuming that the third terminals of the group, 100 337, 338 and 339 are associated with an idle selector switch terminal 337 is not characterized by a busy ground and the holding circuit for relay 150 is opened to cause its release. The release of relay 150 opens the holding circuit for relay 315 and the release of relay 315 opens the energizing circuit for the up-drive magnet 321, thus arresting the upward movement of brush set 330. It 105 will be noted that a circuit is established in position 4 of the sequence switch, Figure 3 from grounded battery through the left winding of relay 315, right contacts of cam 302, commutator 342, brush 344, lower contact of cam 311 to ground through the left contact of relay 315. This circuit through the left winding of relay 315 is momentarily maintained after the circuit through its right winding is opened, in order that brush set 330 will be properly centered upon terminals 337, 338 and 339.

The release of relay 315 establishes a circuit to rotate the sequence switch out of position 4. The circuit to energize sequence 130

switch 300 may be traced from grounded battery through its winding, left lower contact of cam 310 to ground on the left normal contact of relay 315. The sequence switch magnet is now energized through master contact 301 to rotate the sequence switch into position 7. In position 7, a circuit is established to operate relay 315 from grounded battery through its left winding to ground through the lower contacts of cam 302. The operation of relay 315 establishes a circuit to energize magnet 300 to rotate the sequence switch into position 8. This energizing circuit may be traced from grounded battery through the winding of magnet 300, left upper contact of cam 311, to ground through the left contact of relay 315. Upon the rotation of the sequence switch into position 8, the energizing circuit for relay 315 is opened to cause its release. In position 8 of the sequence switch, the trunk conductors 313 and 314 are connected through cams 305 and 306 and brushes 333 and 332 with terminals 338 and 339 and conductors 360 and 361 extending to a subsequent selector switch to be positioned by the sender for completing the connection to a wanted subscriber.

The selector switches controlled by the sender to complete the telephone connection to the wanted subscriber's line and the release of the selector switches upon the termination of the use of the talking conductors by the subscriber, is the same as described in my aforementioned copending application.

From the foregoing description it will be apparent that the combined features of group selection and trunk hunting as applied to selector switches may be utilized to economize in apparatus and the time necessary to complete telephone connections between subscribers and to permit more flexible grouping of trunks in the switch banks.

What is claimed is:

1. In an automatic telephone exchange system, in combination, a selector switch having a movable brush set, a relay operative to control the movement of said brush set, a bank of fixed trunk terminals divided into groups, a sender, means in said sender to maintain said relay operated during a continuous movement of said brush set to select a particular group and an idle trunk in said group, and means associated with a terminal of each group to control said sender.

2. In an automatic telephone exchange system, in combination, a selector switch having a movable brush set and a bank of fixed trunk terminals divided into groups, a sender, means to establish a revertive control of said switch by said sender, and means

to control said brush set in a continuous movement to select a particular group and an idle trunk in said group by the said revertive control exercised by said switch over said sender. 65

3. In an automatic telephone exchange system, in combination, a selector switch having a bank of fixed terminal sets and a set of brushes for cooperation therewith, said sets of terminals being divided into groups, a control relay and operating magnet for said switch, said magnet being under the control of said relay for advancing said brush set in group and terminal hunting movements, a sender, a stepping relay for said sender, two control circuits extending from said switch to said sender, means in said sender for maintaining the operation of said control relay over one of said circuits continuously during the group and hunting movements of said brush set, means operative during the group selection movement of said switch over said other control circuit for intermittently operating said stepping relay, and means in said sender operative upon the termination of group selection and the engagement of said brush set with an idle terminal set for opening both of said control circuits. 70 75 80 85 90

4. In a telephone system, a selector switch having a movable brush set, a bank of fixed trunk terminals divided into groups, a sender, means in said sender to cause continuous movement of said brush set to select a particular group and an idle set of terminals in said group, and means associated with a terminal of each group to control said sender. 95 100

5. In a telephone system, a selector switch having a movable brush set, a bank of fixed trunk terminals divided into groups, a sender, means to operate said brush set under control of the sender to select a group of terminals, and means in the sender responsive to a condition on the terminals of the selected group to cause the brush set to continue its movement without interruption to select a set of terminals in the group. 105 110

6. In a telephone system, a selector switch having a movable brush set, a bank of fixed trunk terminals divided into groups, a sender, means to operate said brush set under control of the sender to select a group of terminals, and means in the sender responsive to a fixed condition on the first set of terminals in each group and to the busy condition on succeeding terminals to cause the continuous movement of said brush set. 115 120

In witness whereof, I hereunto subscribe my name this 24th day of June A. D., 1924.

FRANKLIN A. STEARN.
